(54) **WHEELS, FOR CARRIAGES**

(76) Inventor: **Isaac Van Gorder**

Isaac Van Gorder of Warren, Ohio
Sister's Patent

The Schedule referred to on this Letter Patent and making part of the same, containing a description in the words of the said Isaac Van Gorder himself of his improvement in the construction of wheels, for Wagons, and Carriages.

To all to whom these presents shall come, Be it known that A. C. Isaac Van Gorder of Warren in the County of Trumbull and State of Ohio have invented a new and useful improvement in the manner of constructing wheels, for wagons, and carriages, and that the following is a full and exact description of the construction and operation of said improvement as appre-
hended by me, to wit. The hub or nave of the wheel is made of cast iron, and for a two horse carriage the diameter of the hub for the hind wheel is six and a half inches, with mortises for sixteen spokes, and that of the hub for the fore wheel, six inches, with fourteen mortises, the thickness (or that which in this manner hub would be termed the length) of the hub is two and one fourth inches at the outer edge and three inches at the centre, the eye of the mortises for the spokes is sufficient to admit a iron of one and three fourths inch wide and three fourths of an inch in thickness. Also the centre of the hub is a round tapering hole of one and one fourth inches diameter at the outer end of the hub, and two inches at the inner end, into this hole in the hub is inserted the end of an axle, or journal made of cast or wrought iron and made tapering so as exactly to fill the hole in the hub the axle is made fast by means of a screw bolt inserted into the end of the axle at the outer end of the hub, on which bolt is a head eight square of one and three fourths inch diameter resting against the outer end of the hub. The axle passes from the hub under the axle box and plays in two bears of cast iron which bears are made fast to the under side of the axle box bed by means of six nuts, passing over the axle box bed with iron bars at their lower ends. The beam next to the end of the axle is six inches wide and one fourth inches thick by two and a half inches wide, being fitted on the wide way of the box it is up and down. The length of the beam, three and a half inches on the top edge, and two inches on the lower edge.

With the top edge of the box at each corner and running lengthways of the box is a flange or projecting lip of about $\frac{1}{8}$ of an inch wide, the whole length of the box, and likewise on the contrary of the upper edge of the box, a tongue rising to the same height and running in the same direction with the lips at the corners (the tongue is half an inch wide). These are bedded into the under side of the axle-tree but to keep the box from touching the box lengthways, in which the nail runs.

A plate of iron four inches long two inches wide and of suitable thickness with a hole thro' at each end running across under the box, thro' which plate the lower end of the stirrup paw on which there is, a washer, with a burr at the under side of the plate beginning of which the plate is pressed hard against the under edge of the box to keep it tight to the under side of the axle-tree. The box fast from the hub is made two pieces of cast iron about four inches long and an inch and a half wide. The top piece is, $\frac{5}{8}$ of an inch thick and the lower piece $\frac{3}{8}$ this is the lower piece is made with a cavity in the middle; the other with a hollow on one side and a square projection on the opposite side. The pieces are made in such a manner that when laid together with the hollowing sides next to each other a round hole is formed between them one and $\frac{1}{2}$ inch diameter in which the iron end of the axle plays.

These pieces have holes thro' the ends and are fastened to the axle bedded in the same manner as the iron plate mentioned in the description of the other box. The square projection on the top piece as, mentioned before it, bedded in the wood above to keep it steady to its place.

The axle is of cast or wrought iron, the length to be determined by the width of the carriage, it is intended that when the carriage is put together the inner end of the axle will run within four inches of each other, so that for a carriage or wagon of four feet track, the length of the axle, will be about two feet four inches including that part which goes thro' the hub.

The axle is round and tapers growing smaller from the hub towards the inner end that part which goes into the hub has been already described. The diameter of the axle where it runs in the outside box is one & three fourths

inch being one-fourth of an inch less than its diameter at the end of the hub, which leaves a square shoulder on the axle close to the inner end of the hub, this shoulder bearing against the box and preventing the wheel from pressing inward when in motion. The diameter of the axle taken at the inner end is one and one eighth inches. On the ^{outer} end of the axle is a collar about $\frac{3}{8}$ of an inch wide rising about a quarter of an inch above the circumference of the axle when it passes thro' the inner box. The shoulder of this collar bears, against the inner edge of the box, to prevent the wheel from driving outward, when in motion. When a wrought iron nail is used, the end which goes into the hub, will extend thro' the hub about an inch, on the outside, with a screw-cut on the end, and a burr to screw up against the end of the hub. The other end of the nail will likewise have a screw and burr with a washer in the form of the collar as described in the cast axle,) to work against the inner edges of the box. (In the form of the inside box as above described may be substituted a bolt of wrought iron passing up thro' the axle-travel bed with an eye on the lower end and a burr on the top. The axle-travel bed to be made the same as when the common iron axlebox is used. The spokes, and felloes, and hub of the running wheel to be made in the usual way of making wagons, and carriages.)

That which I claim in the above described machinery is, new and of my own invention, is, the principle of attaching each wheel to its separate axle or journal made fast in the hub and running the wheel on journals, in boxes attached to the axle-travel bed.
